UNITED STATES PATENT OFFICE.

GEORGE F. BLASIER, OF NORTH TONAWANDA, NEW YORK, ASSIGNOR TO BUFFALO BOLT COMPANY, OF NORTH TONAWANDA, NEW YORK, A CORPORATION OF NEW YORK.

OVERHEAD HEATING FURNACE AND BURNER THEREFOR.

Application filed April 6, 1927. Serial No. 181,330.

This invention relates to heating apparatus and more particularly to means for heating the ends of articles such as bolts, said means including a novel construction and arrangement of water-cooled, gas-burners adapted for burning the gases or gaseous mixtures commonly used for such purposes, as for, instances, producer gas.

Heretofore, end heat furnaces for bolt blanks and the like have generally been fired with one or more burners placed either at the back or at the ends of the furnaces. In such furnaces, the end of a blank to be heated is not ordinarily exposed to the direct heat from the burners, the burner chamber being in general relatively large and the blank being heated by indirect heat. Naturally, furnaces of this type consume much fuel and one object of my invention is to have the flame thrown directly downward on the ends of the blanks, preferably from the upper arch or roof of an end heat furnace, preferably one of relatively small volume and depth.

In order to have such a furnace fired from the top, it has been proposed to use individual cast-iron burners placed as close together as possible, but with such arrangements it has been found necessary to keep the heat away from the burner, for, as soon as the burner gets fairly hot, as, for example, when it shows the least sign of becoming red, the burner will back-fire at once. Consequently, it has been proposed to have the nozzle of each burner located some distance above the inner surface of the brick arch, and to have a nozzle of refractory material built in, from the end of the cast-iron part of the burner to the inner surface or under side of the arch.

One object of the invention is to provide a novel and advantageous form of overhead burner suitable for use in the above and similar relations, that is proof against danger of back firing or other damage from overheating and which does not require a refractory nozzle.

According to a preferred embodiment of the invention, the burner is made up of a plurality of inner chambers between two downwardly converging side walls and separated from each other by partitions extending from side wall to side wall and to the top wall, these walls being preferably continuous

for all of said chambers. Gas or a gaseous mixture is supplied from a header through individual pipes to said chambers from which it emerges preferably through slots in the narrow bottoms of said chambers. The converging side walls of said chamber also serve as inner walls of water jackets, the burner as a whole having a generally rectangular cross-section. Water may be supplied to said water jackets at one end near the bottom wall of the burner and outlet means may be provided at the top of the water jackets, near the other end of the burner structure. Preferably, the upper wall or roof of the water space inclines upwardly so that the thermo circulation tendency will operate to carry the hottest part of the water as well as any steam toward the high level outlet for the cooling medium. Preferably, the incline is afforded by making the entire structure of increasing height toward the outlet end.

The burner is preferably positioned across the top of the arch with its lower face substantially flush with the brick work at the under side of the arch in such relation that the jet flame is directed downward on the blanks. The blanks are inserted from the side immediately over a floor of suitable refractory material, preferably inclined downwardly away from the insertion side. The furnace chamber may be made rather small, as compared with the chambers of furnaces in which the blanks are heated by indirect heat, and naturally requires less fuel.

The above and other features of my invention may be more fully understood from the following description in connection with the accompanying drawings, in which:

Fig. 1 is a sectional side elevation of a furnace embodying one form of the invention;

Fig. 2 is a cross-section of the burner;

Fig. 3 is a top plan view of the burner, partly broken away at the top to show the internal structure; and

Fig. 4 is a vertical longitudinal sectional view of the burner.

As shown in Fig. 1, a burner 1, constructed in accordance with the present invention, is mounted in the upper part of the arch of a furnace 2. The furnace 2 comprises a rear arch portion 3, a floor 4 and a suspended arch portion 5 hung on an I-beam 6 which

may be supported in any suitable manner, all of these parts being formed of suitable heat-resisting material. Preferably, the burner 1 is located above and the flame is propagated between the arch portions 3 and 5. This is in marked contrast with arrangements wherein the refractory material covers the metal outlet so that the refractory material constitutes the nozzle from which the flame develops. As shown, rear portion 3 of the arch may be formed of a plurality of superimposed courses each extending forward beyond the next lower course, the burner itself forming the final step or roof 15 of the arch. Preferably, the floor 4 is constructed so that its upper surface has a downward slope away from the side of the furnace where the blanks are inserted.

The burner 1 may be cast iron but is preferably formed by welding rolled steel plates. It comprises inner walls 7, converging from the top of to the bottom, substantially parallel outer walls 8, a bottom or fuel-outlet wall 9 and a top or fuel-inlet wall 10. The converging walls form the side walls of a number of similar burner chambers 11, which are V-shaped in cross-section and are separated from each other by V-shaped transverse walls or partitions 12. The chambers are separately connected at the top with individual pipes 13, connected with a header 14. At the bottom of each chamber 11, is a narrow slot 15 in the lower wall 9, adapted to serve as the nozzle for the gas jet. This nozzle slot ends a substantial distance from the partition walls 12, the length of the slot outlet being in the present case, only about two-thirds the distance between the partitions. Thus the flame heat can be dissipated in the metal endwise of the outlet as well as laterally. Each of the nozzle openings at the bottom of the chambers 11 is shown as a continuous slot but a row of shorter slots or a series of small holes may be used as in ordinary gas stove burners.

Included between the upper and lower walls of the burner and between the converging inner walls 7 and their respectively adjacent outer walls 8, are two chambers 16. Preferably, these chambers are not partitioned transversely, each extending the entire length of all the burner chambers, serving as water jackets to cool the burners. The relatively great vertical height of the jackets as compared with the width of the exposed lower surface ensures an ample supply of the cooling medium free to circulate vertically into and out of the region of greatest heat; also the great length of the bottom surfaces of the jackets as compared with the length of the nozzle slots, ensures proper cooling of the nozzle walls. The water is supplied to the respective jackets 17 at one end, near the lower wall of the burn-

er, through inlet pipes 18 and the hot water and steam escapes from the water jackets at the other end through high level outlets 19. The burner being of greater height at the end outlets than at the inlets, the latter feature also tends to compensate for the higher temperature of the water toward the outlet ends of the water jackets, although this is less important than the factors of the vertical circulation, natural tendency of the 70 colder water to flow along the bottom and great width as well as great length of the jacket bottom as compared with the nozzle slot. 75

From Fig. 1 it will be evident that when 80 a blank 20 is inserted into the furnace 3 from the side, the flame from the burner 1 will be directed downwardly toward the blank and the floor 4, preferably so that the blank 20 will be heated directly by the 85 flame.

It should be understood that the number and sizes of the burner chambers passing through a water chamber may be varied widely and that they may be surrounded by 90 the water instead of merely separated by partitions; also that there may be a plurality of single burners each of the cross-section shown in Fig. 2; also that a plurality of either single burner units, or multiple burner 95 units herein shown, may be arranged end to end or in parallel rows or otherwise. Various other changes may be made in the arrangement and construction of the path and some parts may be used without others, 100 without departing from the true spirit and scope of my invention.

I claim:

1. A furnace for heating articles to very high temperature, consisting of a chamber 105 having a refractory lining and means for heating the articles in said chamber, including a burner set in and discharging downwardly through said refractory lining, said burner including side walls, an outlet wall 110 having burner openings therein, and separate fuel conduits extending through said burner to corresponding burner openings, said burner being constructed for the passage of water therethrough to exert a cooling effect 115 on said side and outlet walls and on said fuel conduits.

2. A furnace for heating articles to very high temperature, consisting of a chamber having a refractory lining and means for 120 heating the articles in said chamber, including a burner set in and discharging downwardly through said refractory lining, said burner including an elongated box-like structure having side walls, an outlet wall forming 125 a bottom member extending between said side walls and having burner openings arranged lengthwise thereof, and separate fuel conduits extending through said burner to corresponding burner openings, said box- 130

like structure having conduit chambers permitting the passage of water therethrough from end to end to exert a cooling effect on said walls and said fuel conduits.

- 5 3. A furnace for heating articles to very high temperature, consisting of a chamber having a refractory lining and means for heating the articles in said chamber, including a burner set in and discharging downwardly through said refractory lining, said burner including a longitudinally extending outlet wall provided with longitudinally extending slots arranged at intervals therealong, longitudinally extending side walls, a wall opposite said outlet wall, and means within said walls to direct fuel independently to said slots and to cooperate with said walls to provide water-jacket space extending from end to end of the burner. 70
- 10 4. A furnace for heating articles to very high temperature, consisting of a chamber having a refractory lining and means for heating the articles in said chamber, including a burner set in and discharging downwardly through said refractory lining, said burner including a longitudinally extending outlet wall having longitudinal slots arranged therealong in correspondence with said fuel inlets, inner walls extending from said fuel inlet wall to said outlet wall on opposite sides of said fuel inlets and said slots and setting off cooling water spaces at the sides of the burner, and transverse partitions between said inner walls to cause each fuel inlet and the corresponding slot to be shut off from all of the rest of said fuel inlets and slots. 80
- 15 5. A furnace for heating articles to very high temperature, consisting of a chamber having a refractory lining and means for heating the articles in said chamber, including a burner set in and discharging downwardly through said refractory lining, said burner including a longitudinally extending outlet wall provided with longitudinally extending slots arranged at intervals therealong, longitudinally extending side walls, a wall opposite said outlet wall, means within said walls to direct fuel independently to said slots and to cooperate with said walls to provide water-jacket space extending from end to end of the burner, water-inlet means communicating with said water-jacket space at one end, and water-outlet means communicating with said water-jacket space at the other end. 90
- 20 6. A furnace for heating articles to very high temperature, consisting of a chamber having a refractory lining and means for heating the articles in said chamber, including a burner set in and discharging downwardly through said refractory lining, said burner including a longitudinally extending outlet wall having longitudinal slots arranged therealong in correspondence with said fuel inlets, inner walls extending from said fuel inlet wall to said outlet wall on opposite sides of said fuel inlets and said slots and setting off cooling water spaces at the sides of the burner, and transverse partitions between said inner walls to cause each fuel inlet and the corresponding slot to be shut off from all of the rest of said fuel inlets and slots. 95
- 25 7. A furnace for heating articles to very high temperature, consisting of a chamber having a refractory lining and means for heating the articles in said chamber, including a burner set in and discharging downwardly through said refractory lining, said burner including side walls, an inlet wall extending longitudinally of said side walls and having fuel inlets spaced therealong, an outlet wall having longitudinal slots arranged therealong in correspondence with said inlets, and means to connect said fuel inlets with said slots and to cooperate with said walls to provide water-jacket space extending from end to end of the burner. 100
- 30 8. A furnace for heating articles to very high temperature, consisting of a chamber having a refractory lining and means for heating the articles in said chamber, including a burner set in and discharging downwardly through said refractory lining, said burner including relatively thin, elongated horizontally extending box-like structure of substantially greater height than thickness, comprising relatively long top, bottom and side walls, and transverse end walls, said top wall having fuel inlets spaced therealong and said bottom wall having longitudinal slots arranged therealong in correspondence with said fuel inlets, 3 spaced apart inner walls extending from said top wall to said bottom and lengthwise of said structure, on opposite sides of said fuel inlets and said slots, so as to set off cooling water spaced on two sides of the burner, transverse partitions between said inner walls to cause each fuel inlet and the corresponding slot to be shut off from all of the rest of said fuel inlets and slots, water inlet means communicating with said water spaced at one end of the burner adjacent said bottom wall, and water outlet means communicating with said water spaces at the other end of the burner and adjacent said top wall. 110
- 35 9. A furnace for heating articles to very high temperature, consisting of a chamber having a refractory lining and means for heating the articles in said chamber, including a burner set in and discharging down- 115
- 40 10. A furnace for heating articles to very high temperature, consisting of a chamber having a refractory lining and means for heating the articles in said chamber, including a burner set in and discharging downwardly through said refractory lining, said burner including a longitudinally extending outlet wall provided with longitudinally extending slots arranged at intervals therealong, longitudinally extending side walls, a wall opposite said outlet wall, means within said walls to direct fuel independently to said slots and to cooperate with said walls to provide water-jacket space extending from end to end of the burner, and of greater cross-sectional area at one end than at the other, water inlet means communicating with said water-jacket space at the end of smaller cross-sectional area, and water outlet means communicating with said water-jacket space at the other end. 120
- 45 11. A furnace for heating articles to a very high temperature, consisting of a chamber having a refractory lining and means for heating the articles in said chamber, including a burner set in and discharging down- 125
- 50 12. A furnace for heating articles to a very high temperature, consisting of a chamber having a refractory lining and means for heating the articles in said chamber, including a burner set in and discharging down- 130

wardly through said refractory lining, said burner including side walls, an inlet wall extending longitudinally of said side walls and having fuel inlets spaced therealong, 5 an outlet wall having longitudinal slots arranged therealong in correspondence with said fuel inlets, inner walls extending from said fuel inlet wall to said outlet wall on opposite sides of said fuel inlets and said 10 slots and setting off cooling water spaces at the sides of the burner, transverse partitions between said inner walls to cause each fuel inlet and the corresponding slot to be shut off from all of the rest of said fuel inlets 15 and slots, water inlet means communicating with said water spaces at one end of the burner adjacent said outlet wall, and water outlet means communicating with said water spaces at the other end of the burner and 20 adjacent said inlet wall, said inlet wall diverging from said outlet wall from the water inlet end toward the water outlet end of the burner.

10. A furnace including an arch of heat- 25 resisting material, a floor of heat-resisting material, and a water-cooled burner in-set, air-tight, to form a surface of the upper part of the arch to direct the flame downward toward the floor.

11. A furnace including side and top enclosing walls of heat resisting material, a floor of heat-resisting material, and a downwardly directed water-cooled burner in-set, air-tight and having its outlet through an

exposed water cooled surface thereof, which is of great area as compared with said outlet. 35

12. A furnace including side and top enclosing walls of heat-resisting material, a floor of heat-resisting material, and a downwardly directed water-cooled burner in-set, 40 air-tight and formed at its outlet with a large area water-cooled surface forming a part of the top interior surface of said furnace enclosing walls.

13. A furnace for heating articles inserted at one side thereof, including an arch of heat resisting material, a downwardly directed water-cooled burner in the upper part of the arch adjacent the inner surface of the front wall of said furnace, and a heat resisting floor sloping downwardly from the insertion side of the furnace. 45 50

14. A furnace for heating articles inserted at one side thereof, including an arch of heat-resisting material, a floor downwardly inclined from the insertion side at the insertion position, and a burner set in the top of said arch and including an exposed lower wall provided with a series of slots arranged longitudinally of said lower wall, means for supplying gaseous fuel to said slots, and water-cooling means for cooling said lower wall at opposite sides of the series of slots. 55 60

Signed at North Tonawanda in the county of Niagara, and State of New York this 4th 65 day of April, A. D. 1927.

GEORGE F. BLASIER.
